PISTON KNUURLING MACHINE

Harold P. Phillips, Hastings, Mich., assignor to
 Hastings Manufacturing Company, Hastings,
 Mich.

Application January 27, 1949, Serial No. 73,085

10 Claims. (Cl. 80—5.1)

1

This invention relates to improvements in piston knurling machine.

The principal objects of this invention are:

First, to provide a manually operated machine for knurling the side walls of pistons by repeatedly passing a knurling tool over a selected portion of the piston while applying a relatively light pressure on the tool.

Second, to provide an inexpensive knurling machine with means for adjustably supporting a piston underneath an oscillatable knurling tool.

Third, to provide means for controlling the stroke or path of a knurling tool relative to a piston to be knurled.

Fourth, to provide simplified means for applying both knurling pressure and movement to a knurling tool.

Other objects and advantages relating to details of my knurling machine will be apparent from a consideration of the following description and claims.

The drawings of which there are three sheets illustrate two forms of a manually operated knurling machine.

Fig. 1 is a side elevational view of one form of the knurling machine.

Fig. 2 is a fragmentary plan view of the machine shown in Fig. 1.

Fig. 3 is a fragmentary vertical cross sectional view taken along the plane of the line 3—3 in Fig. 2 and looking in the direction of the arrows.

Fig. 4 is a fragmentary vertical cross sectional view through the pressure and stroke adjusting mechanism of the machine shown in Figs. 1 and 2 along the plane of the line 4—4 in Fig. 1.

Fig. 5 is a fragmental transverse cross sectional view through a modified form of knurling machine, the section being taken along the plane of the line 5—5 in Fig. 6.

Fig. 6 is a longitudinal cross sectional view taken along the plane of the line 6—6 in Fig. 5.

The machine illustrated in Figs. 1 to 4 consists of a base 1 having a transversely elongated front portion 2 which supports a pair of rods 3 forming a slideway. Slidably mounted on the rods 3 are a pair of end plates 4 each of which has three pairs of downwardly converging grooves 5 formed on its inner face. The grooves 5 are arranged to selectively receive a pair of support plates 6 in downwardly converging relation and the plates are secured in the grooves to hold the end plates together by means of the cap screws 7. The support plates 6 form an adjustable wedge shaped support for supporting

2

pistons of different sizes as indicated at 8, with the upper side of the piston in approximately the same position.

Just to the rear of the transverse portion 2, the base is provided with a bracket 9 having an upright 10 to which the operating lever 11 is pivotally connected. Spaced above its connection to the upright 10, the lever 11 is provided with a pivot pin 12 for pivotally supporting the pressure arm 13. The arm 13 is curved upwardly in front of the pivot 12 so as to overlie the piston 8 and is provided with a head 14 for adjustably receiving the tool holder 15. The tool holder 15 carries the rotatable knurling wheel 16 for engagement with the side wall of the piston 8.

To the rear of the bracket 9 the base 1 is provided with a guide bracket 17 having an upright 18 extending thereabove. As is more particularly shown in Fig. 4, the side of the upright 18 supports an angle shaped clip 19 to form a guide slot 20 between the side of the upright and the clip. The guide slot 20 slidably receives the rear guide portion 21 of the arm 13. It will be noted that the inner surface of the clip 19 is stepped as at 22 to form a shoulder along the side of the slot 20 for receiving the gage block 23. A pin 24 is secured to the clip over the shoulder 22 and the gage block 23 is vertically slotted as at 25 so as to be easily removable from the clip. The guide portion 21 of the arm 13 is provided with a pair of projecting pins 26 (see Figs. 1 and 2) which are arranged to strike against the ends of the gage block as the arm is reciprocated to limit the motion of the pressure arm and lever. Obviously gage blocks 23 of different lengths can be fitted in the clip 19 to vary the stroke of the machine.

The top of the upright 18 is provided with a pivot pin 27 which supports a spring abutment arm 28 on the rear of the machine. The position of the arm 28 relative to the upright can be adjusted by means of the screw 29 extending through the upright and bearing against a portion of the arm 28 radially of the pin 27. The rear end of the arm 28 is engaged with one end of the spring 30 while the lower end of the spring 30 is hooked around the rear end of the pressure arm 13. It will thus be seen that the spring 30 will act to urge the forward end of the pressure arm downwardly about the pivot 12 to press the knurling wheel 16 against the piston. The tension of the spring 30 and therefore the pressure of the wheel 16 can be adjusted by means of the screw 29.

In order to release the pressure on the knurling

wheel 16 as when removing a piston or installing a piston to be knurled, I have provided a release cam 31 pivotally mounted on the side of the upright by the pin 32. The cam 31 is operated by the lever 33 and is adjustable to three positions as determined by the detents 34 engageable with a spring pressed ball 35 carried by the upright 18. Fig. 1 shows the machine and release cam 31 in fully loaded position with the cam 31 engaging the guide portion 21 of the pressure arm at its lowest cam surface. By moving the lever 33 till the intermediate detent 34 engages the ball, the rear end of the pressure arm will be moved downwardly slightly causing the knurling tool 16 to be retracted slightly from the piston. Movement 15 of the release cam to fully release position will of course retract the knurling wheel further.

A preferred method of operation of my machine is to fully release the cam 31 and install the piston 8 on the support plates 6. The tool holder 15 is then adjusted until the knurling wheel engages the surfaces of the piston after which the lever 33 can be moved to either intermediate or fully loaded position depending upon the depth of knurling desired. The operator then manually reciprocates the lever 11 causing the knurling tool to move in an arcuate path over the surface of the piston as indicated by the dotted lines in Fig. 3. With the knurling wheel tightly engaging the piston 8, the release cam 31 will initially move away from the pressure arm. As the knurling tool presses into the piston the pressure arm will slowly rise until it again contacts the release cam 31 indicating that the knurling operation is complete.

The modified form of machine illustrated in Figs. 5 and 6 consists of a base 36 having a transversely extending T-slot 37 formed in its upper surface. An angle shaped work holding bracket 38 is slidably mounted on the base and is provided with a clamping nut 39 engageable with the T-slot for clamping the support in adjusted position. The upright flange of the work support 38 carries a laterally projecting pin 40 which is adapted to project into and support a piston 8 along the vertical flange of the support. The vertical flange is slotted as at 41 and an eye bolt 42 has its threaded shank passed through the slot to the adjusting wheel 43. The piston 8 is clamped tightly against the vertical flange of the work holder by passing a bar 44 through the wrist pin holes of the piston and through the head of the eye bolt. The eye bolt is then drawn up tight by the hand wheel 43.

To the rear of the work support 38 the base 36 is provided with a bracket 45 having an upright 46. An operating lever 47 has its lower end pivotally supported on the upright 46. The lever 47 has a pair of spaced ears 48 projecting from one side thereof and tapped to receive the cap screws 49. The cap screws 49 are alternately engageable with the upper portion of the upright 46 to limit oscillation of the lever 47.

Pivotally secured to a raised portion of the lever 47 is the pressure arm 50 which projects forwardly across the work holder 38 and the piston held thereon. The pressure arm carries the bracket 51 on which the knurling tool 52 is rotatably mounted. The forward end of the pressure arm 50 has a grip or handle 53 formed thereon.

The operation of the second form of my machine is extremely simple. The piston is clamped to the work holder as previously described and the work holder is then adjusted

5 transversely along the T-slot 37 to locate the selected portion of the piston underneath the knurling wheel 52. The operator then oscillates the lever 47 with one hand while exerting a downward load or pressure on the handle 53 and pressure arm 50. The cap screws 49 can be adjusted to determine the length of the knurl to be formed and with a little practice the operator can become proficient in applying the correct pressure to the pressure arm and in oscillating the lever 47 sufficiently to produce the desired depth of knurl.

10 I have thus described two practical forms of my piston knurling machine so that others may reproduce and operate the machine without further disclosure. I have not attempted to illustrate other forms or possible modifications of the machine and do not limit my claims to the particular modifications illustrated.

15 Having thus described my invention what I claim as new and desire to secure by Letters Patent is:

20 1. A machine for knurling pistons comprising a base, a work support transversely adjustable on said base for supporting a piston in a fixed position with its longitudinal axis extending transversely of the base, an operating lever having a handle and being pivotally mounted on said base behind said support and swingable in a vertical longitudinal plane, a pressure arm pivotally secured to said lever at a point spaced from the pivotal connection between said lever and base, a knurling tool carried by said pressure arm and located over said work support to engage a piston thereon, means at one end of said pressure arm for applying a pressure thereto for pressing said knurling wheel against a piston, and stop means on said base to limit the oscillation of said lever and said arm.

25 40 2. A machine for knurling pistons comprising a base, a work support transversely adjustable on said base for supporting a piston in a fixed position with its longitudinal axis extending transversely of the base, an operating lever having a handle and being pivotally mounted on said base and swingable in a vertical longitudinal plane, a pressure arm pivotally secured to said lever at a point spaced from the pivotal connection between said lever and base, a knurling tool carried by said pressure arm and located over said work support to engage a piston thereon, and means at one end of said pressure arm for applying a pressure thereto for pressing said knurling wheel against a piston.

30 45 55 60 65 70 75 3. A piston knurling machine comprising a base, a transversely extending V-shaped work support transversely adjustably mounted on the front of said base, an operating lever pivotally secured to said base to the rear of said support and oscillatable in a vertical longitudinal plane, a pressure arm pivotally connected to said lever above said base, a knurling tool adjustably secured to the front end of said arm to overlie said work holder, an upright secured to said base to the rear of said lever, said arm having a rear portion oscillatable across the side of said upright, a guide clip secured to said upright and lapped upon the rear portion of said arm in opposition to said upright, a gage block removably supported on said clip and held against longitudinal movement with respect thereto, stop pins carried by said arm and engageable with the ends of said gage block, an anchor arm angularly adjustably mounted on said upright, a spring stretched between said anchor arm and the rear

end of said pressure arm to urge said knurling tool toward said work holder, a release cam rotatably adjustably mounted on said upright and having a cam surface engageable with said pressure arm to limit the action of said spring on said pressure arm, and a spring pressed ball engageable between said upright and said cam in a plurality of positions of said cam.

4. A piston knurling machine comprising a base, a transversely extending V-shaped work support mounted on the front of said base, an operating lever pivotally secured to said base to the rear of said support, a pressure arm pivotally connected to said lever above said base, a knurling tool secured to the front end of said arm to overlie said work holder, an upright secured to said base to the rear of said lever, said arm having a rear portion oscillatable across the side of said upright, a guide clip secured to said upright and lapped upon the rear portion of said arm in opposition to said upright, a gage block removably supported on said clip and held against longitudinal movement with respect thereto, stop pins carried by said arm and engageable with the ends of said gage block, an anchor arm angularly adjustably mounted on said upright, a spring stretched between said anchor arm and the rear end of said pressure arm to urge said knurling tool toward said work holder, and a release cam rotatably adjustably mounted on said upright and having a cam surface engageable with said pressure arm to limit the action of said spring on said pressure arm.

5. A piston knurling machine comprising a base, a transversely extending V-shaped work support mounted on the front of said base, said support having adjustable work engaging members to accommodate pistons of different diameters, a manual operating lever pivotally secured to said base to the rear of said support and oscillatable longitudinally of said base, a pressure arm pivotally connected to said lever above said base, a knurling tool adjustably secured to the front end of said arm to overlie said work holder, an upright secured to said base to the rear of said lever, said arm having a rear portion oscillatable across said upright, a guide on said upright and lapped upon the rear portion of said arm in opposition to said upright, a gage block removably supported on said guide and held against longitudinal movement with respect thereto, stops on said arm and engageable with the ends of said gage block, an anchor arm angularly adjustably mounted on said upright, a spring stretched between said anchor arm and the rear end of said pressure arm to urge said knurling tool toward said work holder, and a release cam rotatably adjustably mounted on said upright and having a cam surface engageable with said pressure arm to limit the action of said spring on said pressure arm.

6. A piston knurling machine comprising a base, a transversely extending V-shaped work support mounted on the front of said base, said support having adjustable work engaging members to accommodate pistons of different diameters, a manual operating lever pivotally secured to said base to the rear of said support and oscillatable longitudinally of said base, a pressure arm pivotally connected to said lever above said base, a knurling tool secured to the front end of said arm to overlie said work holder, an upright secured to said base to the rear of said lever, said arm having a rear portion oscillatable across said upright, a guide on said upright and

lapped upon the rear portion of said arm in opposition to said upright, a gage block removably supported on said guide and held against longitudinal movement with respect thereto, stops on said arm and engageable with the ends of said gage block, an anchor arm mounted on said upright, a spring stretched between said anchor arm and the rear end of said pressure arm to urge said knurling tool toward said work holder, and a release cam rotatably adjustably mounted on said upright and having a cam surface engageable with said pressure arm to limit the action of said spring on said pressure arm.

7. A piston knurling machine comprising a base, a work support mounted on said base to support a piston with its axis extending transversely of said base, an operating lever pivotally secured to said base, a pressure arm pivotally connected to said lever at a point spaced from the pivotal connection between said base and said lever, a knurling tool secured to the end of said arm to overlie said work holder, an upright secured to said base, said arm having a portion oscillatable across said upright, a guide to said upright and lapped upon said arm, a gage block removably supported on said upright and held against longitudinal movement with respect thereto, stops on said arm and engageable with the ends of said gage block, a spring connected between said upright and said pressure arm to urge said knurling tool toward said work holder, and a release cam rotatably mounted on said upright and having a cam surface engageable with said pressure arm to limit the action of said spring on said pressure arm.

8. A piston knurling machine comprising a base, work support mounted on said base to support a piston with its axis extending transversely of said base, an operating lever pivotally secured to said base, a pressure arm pivotally connected to said lever at a point spaced from the pivotal connection between said base and said lever, a knurling tool secured to the end of said arm to overlie said work holder, an upright secured to said base, said arm having a portion oscillatable across said upright, a gage block removably supported on said upright and held against longitudinal movement with respect thereto, stops on said arm and engageable with the ends of said gage block, a spring connected between said upright and said pressure arm to urge said knurling tool toward said work holder, and a release cam rotatably mounted on said upright and having a cam surface engageable with said pressure arm to limit the action of said spring on said pressure arm.

9. A piston knurling machine comprising a base, a work support mounted on said base to support a piston with its axis extending transversely of said base, an operating lever pivotally secured to said base, a pressure arm pivotally connected to said lever at a point spaced from the pivotal connection between said base and said lever, a knurling tool secured to the end of said arm to overlie said work holder, an upright secured to said base, said arm having a portion oscillatable across said upright, a spring connected between said upright and said pressure arm to urge said knurling tool toward said work holder, and a release cam rotatably mounted on said upright and having a cam surface engageable with said pressure arm to limit the action of said spring on said pressure arm.

10. A machine for knurling pistons comprising a base, a work support on said base for sup-

porting a piston in a fixed position with its longitudinal axis extending transversely of the base, an upstanding operating lever having a handle and being pivotally mounted on said base, an elongated pressure arm solely mounted by being directly pivotally secured to said lever at a point spaced inwardly from one end of said arm providing a free end and at a point spaced from the pivotal connection between said lever and base, the pivotal mountings of said lever and arm being parallel so that oscillation of said lever will reciprocate said free end lengthwise and said sole pivotal mounting for said arm will allow said reciprocation as well as allow said free end to move toward and from the work, a knurling tool carried by the free end of said pressure arm remote from its pivotal mounting and located over said work support to engage a piston thereon.

means operating upon a portion of said pressure arm for applying a force thereto tending to swing said arm about its pivot relative to said lever for pressing said knurling tool against a piston, and stop means determining the extent of said swinging movement.

HAROLD P. PHILLIPS.
